WILLIAM B. LUCE, OF HINGHAM, MASSACHUSETTS.

TOY FLYING-MACHINE.

984,683.

Specification of Letters Patent. Patented Feb. 21, 1911.

Application filed October 13, 1909. Serial No. 522,374.

To all whom it may concern:

Be it known that I, WILLIAM B. LUCE, a citizen of the United States, residing at Hingham, county of Plymouth, State of Massachusetts, have invented a certain new and useful Improvement in Toy Flying-Machines, and declare the following to be a full, clear, and exact description of the same, such as will enable others skilled in the art to which it pertains to make and use the same, reference being had to the accompanying drawings, which form a part of this specification.

My invention has for its object to provide a novel and attractive toy in the form of an aeroplane which may be sent gracefully through the air for considerable distances.

The various features of novelty whereby my invention is characterized will herein-after be pointed out with particularity in the claims; but for a full understanding of my invention reference may be had to the following detailed description taken in connection with the accompanying drawings 25 wherein—

Figures 1, 2, and 3 are respectively plan, side and front views of a preferred form of my invention, Fig. 3 being on a somewhat larger scale than the other two figures; Fig. 4 is an enlarged view showing a fragment of the device, the holder and starter being shown in section; Fig. 5 is a side elevation of a modified form of my invention; and Fig. 6 is a section taken on line 6—6 of 35 Fig. 5.

Referring to Figs. 1 to 4 of the drawings, A represents a small aeroplane secured upon the front end of a backbone B. C is a flat tailpiece or rudder attached to the rear end 40 of the backbone. These parts may take any desired forms and be constructed of any suitable material; the members A and C being preferably made of light tough cardboard and the member B of wood. Where 45 cardboard or other fairly stiff material is used for the planes no supporting frame work need be provided as these members may be attached directly to the backbone. The planes may, however, be built up in any desired way as I do not wish to be limited to any specific construction of these parts. For the sake of stiffness a thin strip of wood or other suitable material may be attached to the main plane A so as to extend transversely of the backbone. Moreover, a thin stiffening strip such as E, may

extend from the backbone longitudinally of the tailpiece, thereby making the construction lighter than would be the case if the entire backbone were carried to the rear end 60 of the tailpiece. Directly in advance of the main plane is a propeller F, this propeller being conveniently carried upon the end of a shaft G which is journaled in brackets H and H¹ depending from the front end 65 or nose of the backbone. In order to simplify and cheapen the construction, the propeller shaft may conveniently be made of a stiff wire upon one end of which the propeller is soldered or otherwise fastened, the 70 propeller being held away from the bracket H and the nose of the backbone by means of a small sleeve I. A second sleeve K surrounds the wire in rear of the bracket H¹ and, by bending the end of the wire laterally 75 as indicated in Fig. 4 it is prevented from slipping through the sleeve K and the propeller and its shaft are revolvably held in position. On the underside of the backbone is a downwardly-projecting fin or rib L 80 which lies parallel with and in the same vertical plane as the propeller shaft.

M is a handle having a notch m in its upper end of a size to receive the fin or rib L. Projecting laterally from the holder or 85 handle is a revolvable spool N having therein an opening n sufficiently large to receive the sleeve K and a slot n¹ for receiving the bent end g of the propeller shaft. The parts are so proportioned that when the rear end of 90 the fin or rib L is introduced into the notch in the upper end of the holder, while the holder extends at right angles to the planes, the opening n in the spool is aligned with the propeller shaft so that by moving the holder 95 forward the spool may be coupled to the propeller shaft as shown in Figs. 2 and 4; the connection being such that when the spool is turned the propeller shaft must rotate with it, while either may move away 100 from the other in the direction of the axis of the propeller.

I prefer to make the spool as short as may be convenient in order that the holder may be brought as near the center of gravity as 105 possible and thereby prevent the end of the propeller shaft from binding in the end of the spool.

O is a cord or the like which is adapted to be wound upon the spool and to be unwound 110 rapidly when it is desired to set the aeroplane in motion. The slots a¹ should be deep

enough to permit the propeller to attain full speed before being released.

Assuming that the aeroplane has been mounted upon the holder as shown in Fig. 2 and that the cord has been wound upon the spool: Then, upon holding the handle or holder in one hand and giving a sudden pull upon the cord, the propeller will be set in rapid motion and will draw the aeroplane forward and clear of the holder. The aeroplane will now sail gracefully through the air until the energy stored up in the propeller has been expended, whereupon the aeroplane will sail to the ground. I prefer to make the propeller rather heavy in order that considerable energy may be stored up therein, this being accomplished either by making the propeller of heavy sheet metal or by adding weights, such as f , at the outer ends of the propeller blades, or by using both expedients; the mass which it is desired to have in the propeller depending upon the length of the flights which it is desired to have the aeroplane make. Where the outer ends of the propeller blades are weighted this may conveniently be done by placing drops of solder at these points.

In actual practice I have found that an aeroplane constructed in the manner described may be propelled so as to make flights of considerable lengths, soaring gracefully through the air and descending without mishap.

The device heretofore described is in the form of the simple monoplane but the principle of my invention may be applied equally well to biplanes or other forms of aeroplanes. In Figs. 5 and 6 I have shown a biplane construction; P and P' being the two main planes arranged one above the other so as to provide a space between and Q being a box-shaped tail which is connected to the main planes by means of rods or bars R extending rearwardly from the main planes 45 to the four corners of the tail. The propeller S may conveniently be mounted between the main planes and the tail, the rear end t of the propeller shaft T being bent laterally as in the arrangement previously described. In this construction the driving member must be inserted from the rear through the tailpiece and therefore a different kind of holder is required than in the other form. In the drawing I have illustrated a suitable holder in the form of a handle U having at the upper end a supporting platform or guideway U' . A spool V , corresponding to the spool N , is journaled in bearings u and u' at a point directly in rear of the aeroplane when it is in position on the holder.

W is a shaft forming an extension of one of the shafts of the spool and of sufficient

length to extend through the tailpiece and to the rear end of the propeller shaft. The free end of the shaft W is provided with an opening w to receive the propeller shaft and a slot w' to receive the bent portion t of the shaft to form a driving connection similar to that shown in the other construction.

It will be seen that the weight of the aeroplane is carried upon the holder independently of the propelling mechanism so that there is but little friction between the driving shaft and the propeller shaft when the aeroplane begins to move under the impulse given to it by the propeller. In this arrangement a cord X is wound upon the spool and, when the aeroplane is to be projected into the air a quick pull is given upon this cord so as to set the propeller in rapid motion.

While I have shown in detail only two forms of my invention I do not desire to be limited to the particular constructions and arrangements illustrated, but intend to cover all embodiments of my invention falling within the terms of the definitions thereof constituting the appended claims.

What I claim:

1. A toy flying machine comprising an aeroplane, a bracket projecting beneath the aeroplane at the front thereof, a propeller shaft mounted in said bracket and extending in front and rear thereof, a propeller on the front end of the shaft, the rear end of the shaft having a laterally extending projection, a guide rib on the underside of the aeroplane parallel with said propeller shaft, a holder having a slot for receiving said rib, a spool revolvably mounted on said holder and provided with an axial opening to receive the rear end of the propeller shaft, said opening being constructed and arranged to lock the spool and the propeller shaft against relative rotary movement or permitting disengagement between the same in the axial direction.

2. A toy flying machine comprising an aeroplane, a weighted revolvble propeller on said aeroplane, a holder on which said aeroplane loosely rests, a revolvble member mounted on said holder in axial alinement with the propeller shaft, and interlocking shoulders between said member and the propeller shaft arranged to prevent relative rotary movements while at the same time permitting the propeller shaft to disengage itself in the axial direction.

In testimony whereof, I sign this specification in the presence of two witnesses.

WILLIAM B. LUCE.
